WEB DRYING APPARATUS

Hans K. Steinfeld, Swarthmore, Pa., assignor to
 American Viscose Corporation, Wilmington,
 Del., a corporation of Delaware

Application February 7, 1951, Serial No. 209,821

14 Claims. (Cl. 34—114)

1

The present invention relates to an apparatus for drying webs, such as those formed of regenerated cellulose and the like. More particularly, the invention relates to an improved sectionalized drying hood to be used in conjunction with conventional drying rolls now presently employed in drying regenerated cellulose and the like. "Web," as used throughout the specification and claims is intended to include all types of sheet materials, such as textile fabric, paper, films formed from regenerated cellulose, cellulose ethers and esters, various plastic materials, such as polyethylene, Saran, polyvinyl chloride, and the like. For purposes of simplicity the invention will be described as it is applicable to the treatment of a web or film of regenerated cellulose or cellophane, it being understood, of course, that this is not intended in a limitative sense.

It is the generally accepted practice for commercial operation to dry a web of regenerated cellulose by passing it around internally heated rolls or drums. The continuously produced web is passed around a series of such rolls or cylinders, which are arranged in two tiers so that the film or web first comes in contact with or is supported on one side by a roll in the upper tier and then on the other side by a roll in the lower tier, and so on, alternately throughout the length of the train of rolls. The axes of the rolls of the lower tier lie between the axes of the rolls of the upper tier and all of the rolls are rotated at the same peripheral speed.

Even though such a system is now in general use there are a number of disadvantages attendant thereto. When regenerated cellulose film leaves the last treating bath and enters the drying section of the machine, it contains approximately 300 to 400% moisture, which moisture content is usually reduced to 5 to 10% during drying. Therefore, a very substantial volume change takes place during the water removal, which manifests itself in shrinkage, i. e., loss of area and thickness. The shrinkage must be uniform throughout the web in order to produce a uniform product and for production purposes there is always the desire to reduce the shrinkage to a minimum.

To insure even drying of the web, and consequently even shrinkage thereof, it is presently the practice to blow air, which may be cold or heated, over the film or web while passing over the heated drying rolls. This is done to remove the moisture-laden air from contact with the web and to assist in the drying thereof. It is necessary to remove the moisture-laden air from intimate

contact with the web in order to avoid an undesirable equilibrium from being set up between the amount of water in the web and in the air immediately adjacent thereto, which obviously would hinder the attainment of the desired moisture content in the finished product.

This practice of blowing air over the web on the drying rolls has not proven too satisfactory because the supplied air diffuses in an uncontrolled manner over wide areas of the film or web and particularly in a direction parallel to the axes of the drying rolls which causes uneven drying of the film and results in a product of inferior quality. The uneven drying is caused by the edges of the web drying at a faster rate than the center of the web because the supply air hits the edge of the web on both sides thereof. The reason for this is attributed to the fact that the contaminated, moisture-laden air is not exhausted immediately at the source of contamination but is permitted to circulate and recirculate freely over the film surface until it is picked up by the general exhaust system.

It is a general object of the present invention to provide an apparatus or drying system which will overcome the above-mentioned difficulties and disadvantages.

It is another object of the invention to provide an apparatus which will supply air to each integral part of the web at the same rate and immediately remove or exhaust the contaminated, moisture-laden air at the source of contamination.

Another object of the invention is to provide an air supply and exhaust system for each individual dryer roll confined within as limited a space as practical and operational limits will permit and in addition still maintain the advantages of a fully open dryer construction for ready access to the equipment in the event of breaks in the web and for maintenance.

Other objects and advantages of the present invention will be apparent from the description thereof hereinafter.

For a better understanding of the following description of the invention reference should be had to the accompanying drawing which illustrates preferred embodiments thereof, the same not being intended in a limitative sense, and in which—

Figure 1 is a front elevation view showing a drying roll and an air-supply and exhaust system mounted in conjunction therewith.

Figure 2 is a side elevation view of a section of the drying end of a machine,

Figure 3 is a bottom view of the air supply and exhaust system shown in Figure 1.

Figure 4 is a sectional view taken along the line A—A of Figure 1.

Figure 5 is a sectional view taken along the line B—B of Figure 1, and

Figure 6 is a view taken along line C—C of Figure 1.

In general, the objects of the present invention are accomplished by placing above each roll in the upper tier of the train a series of nozzles or small ducts, the series extending parallel to the axis of the roll, which direct air against the web being carried over the roll. Means for removing the moisture-laden air are placed adjacent each set of nozzles above each roll in the upper tier. The nozzles and means for removing the moisture-laden air are positioned in close proximity to the roll surface and are disposed along the entire length of the roll. If desired, the same system may be employed in conjunction with each of the rolls at the lower tier of the train, but only the upper rolls need be supplied with air supply and removal means to accomplish the objects of the present invention.

Referring to Figures 1 and 2 of the drawing, the web drying mechanism comprises two tiers of the drying rolls 2 and 3 all of which are rotatably mounted and positively driven at the same peripheral speed such as by gears, belt, chain and sprocket, etc. Each roll is heated internally by any suitable means (not shown), for example steam, hot water, electric coils, etc. Positioned above each of the rolls 3 in the upper tier is a hood 4 extending longitudinally of the rolls or parallel to the axes thereof. The center line of the hood is preferably offset slightly from a vertical plane through the center line of the roll above which it is positioned and offset in the trailing direction. If desired, the center line of the hood may be in line or coincide with the center line of the roll above which it is positioned.

The hoods 4 are supported above the rolls 3 by the rods or pipes 5 and 6 which extend the length of the roll train, transversely to the rolls and parallel to the direction of travel of the web. The hoods are fastened to the rods as follows: fastened to hood 4 is a yoke-shaped bracket 7 which in turn is fastened to the rod 5 by the U-bolts or hangers 8 and 9 (see Figure 2). Also fastened to each side of the hood 4 are the L-shaped brackets or angle irons 10 and 11 and each of these are in turn fastened to the rod 6 by the U-bolts or hangers 12 and 13 (see Figure 5).

The hoods 4 are divided into two sections or chambers, the air-supply chamber 14 and the exhaust chamber 15. In the upper face of hood 4 near one end thereof there is an opening 16 leading to the air-supply chamber 14 (see Figure 3). Into opening 16 there is inserted the conduit section 17. Another opening 18 in the top of hood opens into the exhaust chamber 15 (see Figure 3), and the conduit section 19 is inserted in the opening 18. The section 17 is connected to a conduit 20 by means of a clamp collar 21, the conduit 20 being in turn connected to the main air duct 22. The air is heated by any suitable means (not shown) while in duct 22 or before entering the same. If desired, the air may be humidified in addition to being heated. Section 19 is connected to a conduit 23 by means of a clamp collar 24, the conduit 23 being in turn connected to a vacuum duct 25.

The air supply chamber 14 is separated from the exhaust chamber 15 by an L-shaped partition

26 (see Figure 5) which extends practically the entire length of the hood 4, being fastened to the end of the hood away from the air supply entrance and at the other end to a curved partition

5 27. Referring to Figure 6, the L-shaped partition is supported by the bracket 28 and is also connected to a partition 29 (see Figure 4) which blocks off the air supply chamber from the lower part of the exhaust chamber formed by the L-shaped partition.

Referring to Figures 1 and 5, the bottom of the air-supply chamber 14 is formed by an L-shaped member 30 which is welded to the partition 26 at one end. The part 30a of the L-shaped member

15 extends upward to form an opening between the wall 4a of hood 4 and the member 30. This opening is divided up into a number of small ducts or nozzles 31 by means of the separating members or partitions 32. The air passes through 20 these nozzles 31 through an elongated opening 33, and down against the web 34 passing over roll 3. The elongated opening 33 is formed by the wall 4a of hood 4 and the angle irons or plates 35 which are adjustably mounted on the L-shaped member 30 by means of bolts 36 which pass through the partitions 35 and the slots 37 in member 30. A plain washer 38, spring washer 39 and nut 40 are placed on each of the bolts 36. As shown in Figure 3 there are three angle partitions 35 employed in the embodiment shown but only one or two or more than three such partitions may be employed if desired.

25 A number of thumb screws 41 are passed through the hood wall 4a and the downwardly extending portions 35a of the angle partitions 35. A nut 42 is placed on each of the thumb screws 41. When the bolts 36 are loosened and the thumb screws 41 tightened the angle partitions 35 will be moved to the right, as viewed in Figure 40 5, thus closing up the opening 33. In this manner the amount of air passing through opening 33 can be easily regulated. When employing a 45 number of adjustable angle partitions 35 the amount of air coming into contact with any part of the web is easily regulated. In this way, even drying across the web is assured even though one portion of the web may contain more moisture than another portion.

Referring to Figure 4, the L-shaped partition 50 26 is supported along its length by the brackets 43, fastened between the partition and the wall 46 of hood 4.

An elongated opening 44 is formed by the L-shaped partition 26 and the wall 46 of hood 4 through which the contaminated, moisture-laden air is drawn into chamber 15.

Referring to Figure 2, the arrows show the direction of flow of the heated air through chamber 14, through the nozzles 31 and opening 33 against the web 34 on the rolls. The air picks up the moisture from the web and then enters the opening 44 to the exhaust chamber 15 of the same hood from which it emerged or of the hood over an adjacent roll. The heated roll drives the moisture through the web and the air picks it up and directs it to the exhaust system. Hence, the film or web is dried on both sides at once. The flow of air may be regulated depending upon the amount of moisture that has to be removed from the web. The moisture content of the finished web may also be regulated by the apparatus of the present invention in that the air coming into contact with the web toward the end of the train may be humidified to the extent necessary.

In this way the desired equilibrium between the moisture in the air and web can be reached.

It is to be noted that the hood 4 is tapered in order to provide for substantially uniform distribution of air over the entire web surface. The hoods 4 should be placed as close to the surface of rolls 3 as is possible under normal operating conditions.

The present invention provides a means of transporting drying air to and from the web area under conditions more controllable than under present practice using known equipment. Webs of any thickness may be dried in the apparatus herein described with slight adjustments in temperature and flow of air where necessary.

The present invention enables one to dry a continuously moving web evenly throughout the same without danger of undue shrinkage, puckering, etc. of the web. The apparatus is easy to construct and install on roll drying machines and is easily controlled. The present invention increases production since the web material can be dried at a higher rate of speed. Numerous other advantages of the invention will be evident to those skilled in the art.

It should be understood that the invention is not limited to the embodiments described and illustrated by way of example and that various structural changes and modifications may be made without departing from the spirit and scope of the invention as defined in the appended claims.

I claim:

1. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending the length of the roll for receiving the saturated medium, a partition extending the length of the housing to separate the exhaust chamber from the supply chamber, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall.

2. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending the length of the roll for receiving the saturated medium, a partition extending the length of the housing to separate the exhaust chamber from the supply chamber, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an

elongated entrance opening positioned directly over the roll and extending the length of the roll along the housing wall opposite the first mentioned wall, separating members dividing the discharge opening into a number of small ducts.

3. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending the length of the roll for receiving the saturated medium, a partition extending the length of the housing to separate the exhaust chamber from the supply chamber, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, separating members dividing the discharge opening into a number of small ducts, spaced members in the elongated entrance opening to connect the housing wall with the partition member, said spaced members lending reinforcement to the partition member with relation to the housing.

4. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending the length of the roll for receiving the saturated medium, a partition extending the length of the housing to separate the exhaust chamber from the supply chamber, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, an elongated nozzle outside of the discharge opening for directing the air from the discharge opening to the roll comprising an extension of the housing wall adjacent the discharge opening and a plate opposite the housing wall extension, said plate facing the wall extension.

5. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending the length of the roll for receiving the saturated medium, a partition extending the length of the housing to separate the exhaust chamber from the supply chamber, the inlet to the supply chamber being

positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, an elongated adjustable nozzle outside of the discharge opening for directing the air from the discharge opening to the roll comprising an extension of the housing wall adjacent the elongated discharge opening, a sliding plate opposite the housing wall extension, said plate facing the wall extension and means for changing the position of the sliding plate with relation to the wall extension to fix the area between the plate and the housing wall.

6. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending the length of the roll for receiving the saturated medium, a partition extending the length of the housing to separate the exhaust chamber from the supply chamber, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, an elongated nozzle outside of the discharge opening for directing the air from the discharge opening to the roll, said nozzle being closer to the roll than the entrance opening of the exhaust chamber.

7. A drying apparatus for drying a travelling web comprising a roll, a housing adjacent the roll comprising a back wall, a front wall adjacent the roll, two side walls, said side walls extending beyond the front wall, a drying medium supply chamber in the housing having a gradual decrease in cross-section as it extends the length of the roll, an exhaust chamber in the housing extending the length of the roll for receiving the saturated medium, a partition extending the length of the housing to separate the exhaust chamber from the supply chamber, the inlet to the supply chamber being positioned at the end of the housing having the larger cross section, the outlet of the exhaust chamber being positioned at the end of the housing having the larger cross-section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, an adjustable nozzle outside of the discharge opening comprising the extension of the housing wall adjacent the discharge opening, a sliding plate

5 facing the wall extension, said plate being attached to the front wall, thumb screws for connecting the plate with the wall extension to change the position of the sliding plate with relation to the wall extension and fix the area between the plate and the wall extension.

8. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending along the length of the roll positioned above the supply chamber, an L-shaped partition extending the length of the housing to separate the exhaust chamber from the supply chamber, one leg of the L-shaped member extending inwardly from one housing wall and extending partially across the cross-section of the housing, the second leg of the member extending downwardly at a 90° angle from the first extended leg in a position parallel with the housing wall, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall.

9. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending along the length of the roll positioned above the supply chamber, an L-shaped partition extending the length of the housing to separate the exhaust chamber from the supply chamber, one leg of the L-shaped member extending inwardly from one housing wall and extending partially across the cross-section of the housing, the second leg of the member extending downwardly at a 90° angle from the first extended leg in a position parallel with the housing wall, the inlet to the supply chamber being positioned at the end of the housing having the larger cross-section, the outlet of the exhaust chamber being positioned at the end of the housing having a larger cross-section, the supply chamber having an elongated discharge opening positioned directly over the roll and extending the length of the roll along one wall of the housing, the exhaust chamber having an entrance opening positioned directly over the roll and extending the length of the roll along the housing wall opposite the first mentioned wall, the entrance opening being formed by the housing wall, the second leg of the L-shaped member and the ends of the housing.

10. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending along the length of the roll positioned above the supply

chamber, an L-shaped partition extending the length of the housing to separate the exhaust chamber from the supply chamber, one leg of the L-shaped member extending inwardly from one housing wall and extending partially across the cross-section of the housing, the second leg of the member extending downwardly at a 90° angle from the first extended leg in a position parallel with the housing wall, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, the discharge opening being separated from the entrance opening by a leg of a second L-shaped member extending the length of the roll, said leg extending inwardly toward the housing wall adjacent the discharge opening from the free end and at a 90° angle to the free end of the downwardly extending leg of the first L-shaped member.

11. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending along the length of the roll positioned above the supply chamber, an L-shaped partition extending the length of the housing to separate the exhaust chamber from the supply chamber, one leg of the L-shaped member extending inwardly from one housing wall and extending partially across the cross-section of the housing, the second leg of the member extending downwardly at a 90° angle from the first extended leg in a position parallel with the housing wall, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, the discharge opening being separated from the entrance opening by a leg of a second L-shaped member extending the length of the roll, said leg extending inwardly toward the housing wall adjacent the discharge opening from the free end and at a 90° angle to the free end of the downwardly extending leg of the first L-shaped member, the discharge opening being formed by the housing wall, the ends of the housing, and the remaining leg of the second L-shaped member disposed vertically to the first leg of the second L-shaped member toward the roof of the housing.

12. A drying apparatus for drying a travelling web comprising a roll, a housing adjacent the roll comprising a drying medium supply chamber extending lengthwise of the roll, said supply chamber having a gradual decrease in cross-section as it extends the length of the roll, an ex-

haust chamber in the housing extending along the length of the roll positioned above the supply chamber, an L-shaped partition extending the length of the housing to separate the exhaust chamber from the supply chamber, one leg of the L-shaped member extending inwardly from one housing wall and extending partially across the cross-section of the housing, the second leg of the member extending downwardly at a 90° angle from the first extended leg in a position parallel with the housing wall, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall, opposite the first mentioned wall, a nozzle positioned at the discharge opening of the supply chamber.

13. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending along the length of the roll positioned above the supply chamber, an L-shaped partition extending the length of the housing to separate the exhaust chamber from the supply chamber, one leg of the L-shaped member extending inwardly from one housing wall and extending partially across the cross-section of the housing, the second leg of the member extending downwardly at a 90° angle from the first extended leg in a position parallel with the housing wall, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, the discharge opening being separated from the entrance opening by a leg of a second L-shaped member extending the length of the roll, said leg extending inwardly toward the housing wall adjacent the discharge opening from the free end and at a 90° angle to the free end of the downwardly extending leg of the first L-shaped member, a series of angle irons attached to the leg of the second L-shaped member, a nozzle for the discharge opening being formed by the downwardly extended legs of the angle irons and the housing wall adjacent the discharge opening.

14. A drying apparatus for drying a travelling web comprising a roll, a housing adjacent the roll comprising a drying medium supply chamber extending lengthwise of the roll, said supply chamber having a gradual decrease in cross-section as it extends the length of the roll, an exhaust chamber in the housing extending along the length of the roll positioned above the supply chamber, an L-shaped partition extending the length of the housing to separate the exhaust chamber from the supply chamber, one leg of the

11

L-shaped member extending inwardly from one housing wall and extending partially across the cross-section of the housing, the second leg of the member extending downwardly at a 90° angle from the first extended leg in a position parallel with the housing wall, the inlet to the supply chamber being positioned at the end of the housing having the larger cross-section, the outlet of the exhaust chamber being positioned at the end of the housing having the larger cross section, the supply chamber having an elongated discharge opening positioned directly over the roll and extending the length of the roll along one wall of the housing, the exhaust chamber having an elongated entrance opening positioned directly over the roll and extending the length of the roll along the housing wall opposite the first mentioned wall, the discharge opening being separated from the entrance opening by a leg of a second L-shaped member extending the length of the roll, said leg extending inwardly toward the housing wall adjacent the discharge opening from the free end and at a 90° angle to the free end of the downwardly extending leg of the first L-shaped member, a series of angle irons attached to the leg of the second L-shaped member, a nozzle for the discharge opening being

10

15

20

25
